UNITED STATES PATENT OFFICE.

WILLIAM E. SHARPS, OF PHILADELPHIA, PENNSYLVANIA.

DESIGN FOR A JAR-CAP.

SPECIFICATION forming part of Design No. 28,980, dated July 5, 1898.

Application filed June 9, 1898. Serial No. 683,036. Term of patent 14 years.

To all whom it may concern:

Be it known that I, WILLIAM E. SHARPS, a citizen of the United States, residing in Philadelphia, Pennsylvania, have invented a new 5 and original Design for a Jar Cap or Cover, of which the following is a specification.

My design for a jar-cap is fully shown in the accompanying drawings, in which—

Figure 1 is a perspective view of the cap, 10 and Fig. 2 is a transverse section of the same.

The essential features of the design are a flat rim, from the outer edge of which depends a threaded flange, while from the inner edge of the rim depends a deep rounded central cup.

15 In the drawings, 1 represents the flat an-

nular rim, 2 the outer depending threaded flange, and 3 the deep rounded central depending cup.

I claim—

The design for a jar-cap substantially as described and as shown in the accompanying drawings.

In testimony whereof I have signed my name to this specification in the presence of two subscribing witnesses.

WILLIAM E. SHARPS.

Witnesses:

WILL. A. BARR,
JOS. H. KLEIN.
